UNITED STATES PATENT OFFICE.

HUGH REID, OF SPRINGBURN, AND DAVID MACNAB RAMSAY, OF MOUNT FLORIDA, SCOTLAND.

LOCOMOTIVE.

No. 805,999.

Specification of Letters Patent.

Patented Nov. 28, 1905.

Application filed July 1, 1904. Serial No. 215,085.

To all whom it may concern:

Be it known that we, HUGH REID, a resident of Springburn, in the county of Glasgow, Scotland, (whose postal address is Hyde Park 5 Works, Springburn, Glasgow, Scotland,) and DAVID MACNAB RAMSAY, a resident of Mount Florida, in the county of Glasgow, Scotland, (whose postal address is 15 Florida street, Mount Florida, Glasgow, Scotland,) subjects 10 of the King of Great Britain and Ireland, have invented certain new and useful Improvements in Locomotives, (for which application for British Patent No. 10,311, dated May 5, 1904, has been made,) of which the following is the 15 specification.

This invention relates to that class of locomotives which are provided with electric motors for their axle-driving means and which carry upon their own trucks an isolated steam 20 and electric generating plant for supplying electric current to said motors. In such locomotives as hitherto generally constructed non-condensing reciprocating engines have been used for driving the dynamos generating 25 current for the propulsion of the locomotive and other vehicles connected thereto by electric motors carried on the running axles. Such non-condensing engines have little more efficiency than the ordinary type of locomotive-engine, and as it is necessary in order 30 to raise steam with sufficient rapidity to employ a draft in the boiler-uptake, and as it is at the same time practically impossible to carry sufficient water for condensing purposes, 35 or even if a condenser were otherwise possible it is inexpedient to use the water of condensation in the boiler, owing to the lubrication necessary in such engines and the consequent contamination of that water with lubricant, it has therefore hitherto been impracticable to combine a condenser with such apparatus. 40

The invention has for its object to overcome these difficulties and the objections hitherto inherent in such machines and which have prevented their adoption and to provide a locomotive of greatly-increased efficiency the power capacity of which is comparatively unlimited and which by utilizing the water 45 of condensation over and over again in its boiler is to a large extent independent of water-supply.

In order that the invention and the manner of performing the same may be properly un-

derstood, we hereunto append three sheets of 55 explanatory drawings, throughout which similar reference-letters indicate like parts, and in which—

Figure 1, Sheet 1, is a side elevation; Fig. 2, Sheet 2, a longitudinal section; and Figs. 60 3 and 4, Sheet 3, respectively a sectional plan and a sectional end elevation showing (to some extent diagrammatically) an example of the application of our improvements.

In carrying out the invention according to 65 the example shown diagrammatically in the drawings—an example more particularly adapted for the working of heavy goods and passenger trains over long distances—we employ upon a truck A, carried upon two bogies 70 B, a boiler C of modified locomotive type (but which might be of any other suitable type) supplying steam to a turbine D of Parson's type, (but which might be of any other suitable type, such as the "Curtis".) The turbine D is directly coupled to an electric generator E of the multiphase type and also to an exciter F for the generator and to a centrifugal air-pump G, used for a purpose hereinafter explained. The generator E supplies 80 current to a series of similar motors H, geared (by gearing inclosed in gear-cases J) to and adapted to drive the axles K of the bogie-wheels. A controller, rheostat, and other apparatus (not shown) are provided for controlling and regulating the pressure and volume of the current generated and the speed 85 of the locomotive.

In order to develop the full efficiency of the turbine D, and so that the condensed steam 90 may be utilized for hot boiler-feed, a condenser is employed the condensing-surfaces of which are cooled by a current of air drawn or impelled over them. This condenser in the present example consists of three series of 95 tubes arranged along the sides and over the top of the structure inclosing the mechanism. The tubes are connected at opposite ends to two headers M N, to one, M, of which exhaust-steam from the turbine D is led and in 100 the other, N, of which vacuum is maintained by the centrifugal air-pump G, the water of condensation being discharged into a hot-well, from which the boiler is fed by feed-pumps W of ordinary reciprocating type. A pump 105 Y maintains forced lubrication of the various bearings. The sets of tubes L are inclosed in casings O, and each casing O is fitted with

a series of louvers, those louvers P along the sides of the structure facing oppositely to those louvers R upon the roof of the structure, so that a current of air is caused to flow 5 in at the side louvers P and out at the top louvers R when the locomotive is running in the one direction and in at the top louvers R and out at the side louvers P when it is running in the opposite. Means of well-known 10 kind are provided for closing ony one or more of the sets of louvers, such means consisting of either rods attached to and operating the louvers, which in that case are hinged, or sliding shutters arranged in the casing behind 15 the louvers, which may then be fixed. The air passing in at the louvers passes over the condenser-tubes L, condensing the steam therein and itself becoming heated. The exit-louvers over the series of tubes in the casing 20 nearest the steam-generator and to which the exhaust-steam first has access are normally kept closed, and the air heated in its passage over what are thus the hottest tubes of the condenser is led from that casing to the fire-box of the boiler C by ducts S. When the 25 locomotive is in motion, the velocity thus given to the air is normally sufficient to maintain a blast-pressure in the furnace of the boiler; but in order to augment when necessary the pressure thus available and to provide 30 a current of air over the condenser-surfaces when the locomotive is stationary a fan T, preferably driven by an electric motor, is provided. The outlet of the fan is connected 35 by a two-way valve U to the ducts S, so that the air can be either led from those ducts directly to the fire-box or drawn through the lower duct from the condenser by the fan and forced into the fire-box or smoke-box, or both 40 fire-box and smoke-box, of the steam-generator.

Although it would appear preferable to force into the boiler fire-box only the air from the first of the series of condenser-compartments, as air sufficient to maintain a blast and of a higher temperature than if it were taken from all the compartments at the same time is so obtainable, yet the whole or any part of the air from the condensing-surfaces may be 45 led or forced into the fire-box of the boiler.

As the use of a condenser normally deprives the boiler of the blast, which is necessary in the conditions under which a locomotive-boiler works to maintain a head of steam, 50 it is clear that our method of utilizing the air which has first taken up heat in a condenser to maintain a draft in the boiler either by the velocity it has due to the speed of the locomotive or by velocity given to it by a fan, 55 or by a combination of both, has great advantage in that not only is an adequate draft easily maintainable with small expenditure of power comparatively to the existing practice of obtaining it by means of the blast of the 60 exhaust, but also the fact that the air used for 65

maintaining this draft has obtained its heat from the steam condensed, makes for high thermal efficiency, an efficiency not so economically obtainable by air otherwise heated when the latent heat of the steam or of the waste 70 furnace-gases has been lost.

It will be seen that it is only with the combination of certain of the integers hereinbefore specified that it is possible to construct an effective locomotive of this type, for, first, 75 it is practically impossible to use the hot water of condensation from reciprocating engines directly for boiler-feeding in that it contains lubricant, which it is impracticable under the conditions to eliminate from it, but as turbines do not require internal lubrication the hot water of condensation from them is pure and may be used in what may be termed a "closed circuit" quite indefinitely; secondly, 80 it is impracticable to carry sufficient water to 85 effectively condense the steam in a condenser in which the cooling medium is water and therefore air is used by us as the cooling medium; thirdly, it is necessary under the conditions to maintain a draft in the combustion-chamber, 90 flues, and smoke-box of the steam-generator, and this can be done effectively when air previously heated in the condenser or by waste 95 furnace-gases is used for that purpose.

It is obvious that the details of construction of the improved locomotive may be largely varied without departing from the spirit of the invention and that the various integers may be arranged in alternative ways and may be carried upon any convenient number of trucks the running-gear of which and the electric motors for driving the wheels of which may be arranged to satisfy any particular conditions—for instance, as regards adhesion and tractive effort—while supplies of fuel and of water for making up incidental losses may be carried upon a separate tender.

The electric generators and motors employed may be of any suitable type and the motors may be arranged to drive any number of the train-axles as well as or instead of those of the locomotive, while the turbine or turbines used may be of any type other than that shown and described by way of example. For instance, they may be of Curtis 105 type.

Instead of a fan a blower or an ejector may be used to maintain the draft in the boiler, and this draft may be caused either by forcing the air into the fire-box, as hereinbefore 110 described, or by induction, and the air used for maintaining the draft may be arranged to be heated by the waste furnace-gases instead of or in addition to by passing through 115 the condenser. Vacuum may be maintained in the condenser by any suitable form of apparatus and in some cases may be dispensed with, the exhaust-steam being merely condensed for use as feed-water, which may be supplied to the boiler either by feed-pumps, 120 125 130

as described, or by injectors, while the cooling effect of the air may in some cases be assisted chemically or by water-spray. Instead of a single turbine and a single electric generator any number of either may be used. In some cases superheaters of any type may be used.

5 A locomotive made according to the invention has numerous advantages over those hitherto proposed or used. For example, it is of particular advantage in those countries where water is scarce, and since its mechanism may readily be entirely inclosed in countries where dust-storms are prevalent or where 15 the winter is severe, and owing to the high economy of the combined turbine and condenser, aided by the utilization of the hot water of condensation for boiler-feed and of the heat given up to the air in the condenser, or 20 by the waste furnace-gases, or both, like horsepower is developed with a smaller steam consumption, a lesser quantity of fuel, and a lesser weight of machinery, such a combined steam electric locomotive affording all the advantages 25 of the various electric systems of railroad propulsion without the disadvantages and cost of surface or overhead conductors or of generating-stations, and when such a locomotive is operated with other vehicles 30 having electric motors attached to their axles the weight of the locomotive may be materially reduced, as this is not required for adhesion, there then being very little or no draw-bar pull.

35 In the claims it is to be understood that the words "a number" include one or more than one of each element to which they are applied.

We claim as our invention—

40 1. A motor-car carrying an isolated steam electric generating plant, having a steam-turbine in combination with an air-cooled condenser consisting of piping for the exhaust-steam, means for maintaining a vacuum therein, and means for producing a current of air 45 therein, as described.

2. A motor-car carrying an isolated steam

electric generating plant, having a steam-turbine in combination with an air-cooled condenser consisting of piping for the exhaust-50 steam, means for maintaining a vacuum therein, an air-chamber in which said piping is located, means for producing a current of air therein, and means for introducing air heated therein into the steam-generator of the plant 55 to maintain combustion, as described.

3. A motor-car carrying an isolated steam electric generating plant, having a steam-turbine in combination with an air-cooled condenser consisting of piping for the exhaust-60 steam, means for maintaining a vacuum therein, an air-chamber in which said piping is located, means for producing a current of air therein, means for introducing air heated therein into the steam-generator of the plant 65 to maintain combustion, and a structure inclosing said isolated plant and having said air-chamber located in its walls and roof and provided with openings to the outside, as described. 70

4. A motor-car carrying an isolated steam electric generating plant, having a steam-turbine in combination with an air-cooled condenser consisting of piping for the exhaust-steam, means for maintaining a vacuum therein, an air-chamber in which said piping is located, means for producing a current of air therein, means for introducing air heated therein into the steam-generator of the plant to maintain combustion, a structure inclosing 75 said isolated plant and having said air-chamber located in its walls and roof and provided with openings to the outside, and shutters for said openings, some of said shutters projecting forward and some rearward, as described. 80 85

In testimony whereof we have signed our names to this specification in the presence of two subscribing witnesses.
